BUSH

Charles Greif Raible, Shaker Heights, Ohio, assignor to The Fanner Manufacturing Company, Cleveland, Ohio, a corporation of Ohio

Application May 7, 1934, Serial No. 724,342

5 Claims.

(Cl. 27—99)

This invention relates to a tap or faucet bush used in conjunction with a beverage barrel or keg and has for its primary object the production of an improved bush which is simple in construction, efficient, and inexpensive to manufacture.

A further object of the invention is to provide an improved bush for the purpose indicated which has a normally closed valve controlled opening therein through which the beverage may be introduced into the barrel or keg in filling the same and through which the beverage may be withdrawn at will.

A further object of the invention is to provide an enclosed resistable means for maintaining the valve in normally closed position to thereby prevent injury to the resistable means and to prevent dirt or other objectionable matter from becoming deposited within the barrel.

With the objects above indicated and other objects hereinafter explained in view, the invention consists in the construction and combination of elements hereinafter described and claimed.

Referring to the drawing,

Figure 1 is an elevational view of a tapping system embodying the present invention, certain portions being shown in cross-section to more clearly illustrate the construction;

Fig. 2 is a vertical cross-sectional view of a tap or faucet bush embodying the invention and upon an enlarged scale;

Fig. 3 is a top plan view taken along line 3—3 of Fig. 2; and

Fig. 4 is a vertical sectional view showing the valve means with the movable valve member in open position.

In the drawing 10 indicates a barrel or keg of the usual construction adapted to contain a beverage such as beer, and consists of a plurality of slats 11 secured together in the usual manner and having the top or head 12 secured within the outer ends of the slats. The barrel 10 also has the usual bottom of identical construction with the top 12 but not shown in Fig. 1 to which reference should be had.

The head 12 is provided with an opening 13 extending therethrough and of any desired diameter, which receives the screw threaded end of a bush 14. The bush 14 is secured to the head within the opening by screwing the threaded end of the bush into the opening, the screwing of which causes threads to be cut into the wood adjacent the opening. The bush 14 is provided with a laterally extending flange 15 which engages with the outer surface of the head 12 and limits the inward movement of the bush, at the same

time producing a tight connection. The bush 14 has a cylindrical hollow extension 16 formed integral therewith and extending coaxially, the upper end of the extension being provided with a laterally extending flange 17.

A tap attaching device 18 has a hollow body portion 19 the lower end of which is enlarged as at 20, and is provided with inwardly extending lugs 21 spaced diametrically opposite to each other. The laterally extending flange 17 on the extension 16 is provided with diametrically opposite slots not shown but which are of a size to permit the passage therethrough of the lugs 21. This construction is such that after the lugs 21 have passed beneath the extension 16 rotation of the body portion 19 causes the lugs to be moved into clamping engagement with the flange 17. This construction is of the type generally known as the bayonet type of connection. Movable mounted within the body portion 19 is a member 22 provided with an axial opening there-through, the lower end of the member 22 having a reduced end portion upon which a rubber washer 23 is securely mounted. This rubber washer 23 is adapted to engage with the upper surface of the extension 16 to provide a liquid tight connection. The upper surface of the extension 16 is convex, as shown at 24, so as to provide a tight connection irrespective of the alignment of the cooperating members.

The upper end of the body member 19 is exteriorly screw threaded at 25 while the adjacent portion of the member 22 is likewise exteriorly screw threaded at 26, the screw threads however extending in opposite directions. A wing nut 27 is adapted to cooperate with the screw threads 25 and 26 on the adjacent ends of the body portion 19 and the member 22, and upon rotation of the wing nut in one direction the member 22 is moved downwardly as shown in Fig. 1 to cause the washer 23 to be rigidly seated upon the outer end of the extension 16. When the wing nut 27 is rotated in the opposite direction the member 22 is moved upwardly with the result that the washer 23 is removed from engagement with the extension 16. The body portion 19 has a transverse slot provided in its wall through which extends one end of a nipple 28. The inner end of this nipple is secured to the member 22 in any desired manner and moves therewith, the movement being limited by the size of the slot. This nipple has an opening extending therethrough and is in communication with the opening provided in the member 22. The exposed end of the nipple 28

has secured thereto one end of a flexible hose 29, the other end of the hose being adapted for connection with any suitable source of pressure.

A tap rod 30 has an opening extending therethrough and is adapted to be disposed within the tap connecting device 18 as shown in Fig. 1. The rod is inserted at the upper end of the member 22 and through the opening provided therein and lowered until the end of the rod is positioned at the proper location with respect to the bottom of the barrel. The outer end of the tap rod, which is not shown herein, is of course provided with the customary tap through which the beverage is discharged, the same being withdrawn from the interior of the barrel. To provide a secure and pressure tight connection between the tap rod 30 and the member 22 an exteriorly screw threaded member 31 cooperates with interior screw threads provided in the outer end of the member 22 and is adapted to be rotated into engagement with a rubber washer mounted within the member 22. A lever 32 is formed integral with the member 31 to enable the member 31 to be readily turned and by turning the member 31 in one direction the rubber washer is caused to contract and grip the tap rod 30, while movement in the opposite direction causes the pressure on the rubber washer to be relieved so that the tap rod may be either withdrawn or inserted as desired. It is to be understood that the beverage within the barrel is readily withdrawn through the tap rod 30 due to the pressure created within the barrel through the medium of the pressure hose 29.

The foregoing description, while forming no part of the present invention is typical of one of a number of tapping systems and is illustrated here for the purpose of more clearly disclosing applicant's invention and therefore it should be understood that the invention is not to be limited to its use with any particular type of tapping system.

It is the accepted practice at the present time to supply barrels or kegs to the trade containing at least one bung or tap bush such as indicated at 45 14. A cork or other stopping means is inserted in the opening of the cylindrical extension 16, which acts as a seal, but frequently after the beverage has been removed from the barrel this precaution of plugging the opening is overlooked 50 or carelessly pursued, with the result that certain objectionable matter enters through the exposed opening and becomes deposited in the barrel. In many cases this deposit cannot be removed and consequently the beverage introduced therein is 55 off flavor.

The interior of the barrel is subjected to a spraying operation through the usual opening provided in the side to provide an impervious coating 33, such as pitch. This coating, in many instances, is an eighth of an inch in thickness and the pitch is sprayed at a temperature of approximately 400° F. and, of course, covers all exposed surfaces within the barrel.

It is the primary feature of the present invention to provide a valve means for maintaining the opening through which the beverage is introduced or withdrawn in normally closed position, said means being under tension and the means enclosed or encased in such a manner as to protect the same from the heat of the pitch when the latter is sprayed upon the interior of the barrel, as the high temperature of the pitch and the subsequent hardening of the same would have a disastrous effect upon the tension means and 75 render the same either inoperative or at least in-

effective. Additionally, by providing a valve means which is normally closed, it is practically impossible for any foreign matter to pass through the opening and into the interior of the barrel.

While various types of valve control means 5 may be employed for obtaining the advantages heretofore set forth, in the present instance a cylindrical member 34 is provided of substantial U shape in cross-section to provide a substantially continuous axial groove 35 in its upper surface, as more clearly shown in Figs. 2 and 3. 10 This member 34 is provided with an axial opening 36 in alignment with the opening provided in the circular extension 16 of the bung bush 14. The bottom of the opening 36 flares outwardly 15 at 37 to provide a valve seat, the surface of which should be preferably ground in order to produce a fluid-tight connection, this valve seat being more clearly shown in Fig. 4. A movable valve member 38 is provided with a valve seat 20 engaging portion 39 which is complementary tapered and preferably ground so as to tightly engage the valve seat 37 when in cooperating engagement. The valve member is provided with an upper surface 49 which is tapered downwardly in a direction away from the pivot connection so as to tend to force any engaging element away from the pivot connection. This movable valve member 38 has an extension 40 which projects through a slotted opening 41 30 provided in the member 34 and is pivotally connected to the member 34 by means of a pin 42 having its ends secured within the member 34 as more clearly shown in Fig. 4. This extension 40 has an integral ear 43 which extends upwardly 35 and is normally disposed within the groove 35. A spring 44 is disposed within the groove 35 and a portion thereof extends through an opening 45 provided in the ear 43. This spring is of sufficient strength to cause the movable valve 40 member 38 to assume a normally closed position but will yieldably permit the valve member to be moved away from the valve seat by the use of a proper implement or projecting the tap rod 30 through the opening into engagement 46 with the movable valve member, as more clearly shown in Fig. 1. A stop 46 may be provided upon the member 34 within the groove 35, as shown in Fig. 3, for engagement by the adjacent ends of the spring 44 so as to prevent the wire from 50 creeping out of alignment and accidental disengagement between the spring 44 and the movable valve member.

The member 34 is adapted for attachment with the bung bush 14 as shown in Fig. 2, and 55 it is preferable to provide a recessed portion 47 on the bottom of the bung bush within which the adjacent end of the member 34 may be disposed. Aligned openings are provided in the member 34 and the bottom of the bung bush 14, 60 the latter being screw threaded to receive the screw threaded ends of attaching screws 48. While it is desirable that the member 38 be made as a separate and detachable element with respect to the bung bush 14, it is, of course, understood that this construction may be made integral for the purposes intended, but it should be understood that the bung bush and valve means are intended for insertion into the barrel as a unitary structure.

In employing the valve means embodying applicant's invention, the bung bush to which it is attached is inserted in the head of the barrel in the manner already explained, and subsequently the spraying apparatus is introduced 7

through the opening provided in the side of the barrel.

While I have described the preferred embodiments of the invention, it is to be understood that I am not to be limited thereto inasmuch as changes and modifications may be resorted to without departing from the spirit of the invention as defined in the appended claims.

Having thus described my invention, I claim:

10 1. A tap or bung bush comprising a body portion adapted for insertion in a barrel or keg and having an opening therethrough, a movable valve member mounted on said body portion and adapted to close said opening, means operatively connected to said movable valve member for maintaining the latter in normally closed position, and means for enclosing said last mentioned means.

2. A tap or bung bush comprising a body portion adapted for insertion in a barrel or keg having an opening therethrough and an enclosed recess therein, a movable valve member pivotally mounted on said body portion and adapted to close said opening, and resilient means positioned within said recess operatively connected to said movable valve member for maintaining the latter in normally closed position.

3. A tap or bung bush comprising a body portion adapted for insertion in a barrel or keg and having an opening therethrough, a member connected to said body portion and having an opening therethrough, said member also having a groove in the surface or end thereof ad-

jacent said body portion, a movable valve member mounted on said member and adapted to close said opening therein, and a spring member disposed in said groove and operatively connected with said movable valve member for maintaining the latter in normally closed position. 5

4. A tap or bung bush comprising a body portion adapted for insertion in a barrel or keg and having an opening therethrough, a member connected to said body portion and having an opening therethrough, said member also having a groove in the surface or end thereof adjacent said body portion, a movable valve member pivotally mounted on said member and adapted to close the opening therein, and resilient means disposed in said groove and operatively connected with said movable valve member for maintaining the latter in normally closed position. 10 15

5. A tap or bung bush comprising a body portion adapted for insertion in a barrel or keg 20 and having an opening therethrough, said body portion also having a recess in the bottom thereof, a member having its adjacent edge disposed in said recess and connected thereto, said member having an opening therethrough, a movable 25 valve member pivotally connected to said member and adapted to close the opening therein, and resilient means enclosed within said member operatively connected with said movable valve member for maintaining the latter in normally 30 closed position.

CHARLES GREIF RAIBLE.
